(73) Assignee: **Ring Barers L.L.C.**, Seattle, WA (US)

An ornamental design for a combined naval ring and logo portion, as shown.

(**) Term: **14 Years**

DESCRIPTION

(21) Appl. No.: **29/161,670**

FIG. 1 is a front view of combined naval ring and logo portion suited to the positioning of a logo or the like;

(22) Filed: **May 31, 2002**

FIG. 2 is a rear view of the naval ring shown in FIG. 1;

(51) LOC (7) Cl. **11-01**

FIG. 3 is a first side view of the naval ring shown in FIG. 1; and,

(52) U.S. Cl. **D11/1**

FIG. 4 is a second side view of the naval ring shown in FIG. 1.

(58) Field of Search **D11/1, 2, 26, 43, D11/75; 63/3, 12, 13, 29.1**

The dashed lines are shown in the views for illustrative purposes only and form no part of the claimed design, because they (1) represent non-statutory functional subject matter, (2) represent environment for the naval ring and/or (3) they are non-limiting, and therefore disclaimed aspects of the design. The uppermost solid line defines the upper boundary of the claimed design, and the lowermost solid line defines the lower boundary of the claimed design.
